Primary Examiner — Rosemary K Tarcza*Assistant Examiner* — Nathaniel D Buckner(74) *Attorney, Agent, or Firm* — Nixon & Vanderhye PC(57) **CLAIM**

The ornamental design for a drive array, as shown and described.

DESCRIPTION

FIG. 1 is a front perspective view of a design of a drive array;

FIG. 2 is a rear perspective view thereof;

FIG. 3 is a front view of thereof;

FIG. 4 is a back view thereof;

FIG. 5 is a side view thereof;

FIG. 6 is a top view thereof; and,

FIG. 7 is a bottom view thereof.

The broken lines show environmental structure and form no part of the claimed design.
